CENTRIFUGAL TIMING SWITCH

Ellis Burrell, Rochester, N.Y., assignor, by mesne assignments, to the United States of America as represented by the Secretary of the Navy

Filed June 2, 1950, Ser. No. 165,977

6 Claims. (Cl. 200—80)

This invention relates to centrifugal unshorting switches. In one form of centrifugal timing switch of the character described in Rickmeyer 2,435,602 and 2,435,603, a conductive fluid (mercury) is moved by the pressure of centrifugal force to control an electrical circuit. The switch provides a predetermined time delay in opening or closing an electrical circuit by the flow of the conductive fluid through a plurality of restricted passages in response to centrifugal pressure set up in the switch by the rotation of the mechanism in which the switch is mounted. One important application of this type of switch is in electric fuzes for use in artillery projectiles to remove a short circuit across an electrical detonator a desired interval after a projectile is fired. Usually a tubular shell is divided into two compartments by a restriction partition. The conductive fluid (mercury) is confined in one compartment before the actuation of the switch and the other compartment acts as a receiver for the fluid. The compartment initially filled with mercury is provided with two electrical contact members insulated from each other and electrically communicating with the interior of the compartment. Usually one contact member is the tubular shell and a second contact member is mounted in one end of the shell and insulated from it. The mercury bridges the gap between the two contacts to complete the electrical circuit through the switch. The restriction partition between the two compartments is normally provided with restricted passages through which the mercury is caused to flow by the pressure of centrifugal force resulting from the spinning of the switch, e.g. during the flight of a projectile. The restricted passages are capable of preventing the passage of the mercury under the blows and impacts occurring during normal handling, but upon rotation of the switch about an axis at one side of the restriction partition, centrifugal pressure will force the conductive fluid through the restricted passages from one compartment into the other. The electrical circuit is broken when a sufficient volume of mercury has flowed through the restricted passages to uncover the end face of the second contact and open the conduction path through the mercury. The time required to break the electrical circuit is dependent upon the volume of mercury that must flow through the restriction partition to uncover the end face of the second contact and the rate of flow of the mercury through the restricted passages, the latter factor being determined by the pressure against the partition due to centrifugal force and the nature of the restricted passages through the restriction partition.

Inherent structural and operational difficulties are present when mercury is used to make or break an electrical circuit. This conductive fluid often deposits a film of an oxide of mercury across the switch which establishes a high resistance short circuit between the contacts after sufficient mercury has flowed through the restricted passages to open the electrical circuit. Furthermore, it is extremely difficult to establish low resistance contacts with the mercury, and normally a special sleeve of copper or

other material having a high affinity for the mercury must be provided within the tubular shell to obtain the desired low resistance contact between the metal shell and the mercury. Similarly, a special ring of copper must normally be pressed onto the second contact to obtain the desired contact resistance with the conductive fluid. Copper has a strong tendency to amalgamate with the mercury causing contamination and the formation of a sludge within the compartment initially filled with the conductive fluid which often adversely affects the flow characteristic of the mercury.

It is an object of the invention to provide a centrifugal unshorting switch in which a positive short circuit is normally established between two electrical terminals without any possibility of a high resistance between the terminals before the electrical circuit is broken.

A further object of the invention is the provision of a centrifugal unshorting switch which eliminates any possibility of the establishment of a high resistance short circuit between the terminals after sufficient mercury has flowed through the restriction partition to open the electrical circuit, and in which it is unnecessary to utilize elements having a strong tendency to amalgamate with the mercury which may cause contamination and the formation of a sludge within the switch.

The invention essentially consists of utilizing a continuous shorting strip of metal formed with a frangible neck portion instead of relying upon a conductive fluid to short circuit the contact members, initially containing the mercury within a fixedly positioned, hollowed cylindrical container closed at one end and having a restriction partition sealed across the open end thereof, and telescoping the container within a light, movable, cup-shaped member which normally rests against the frangible neck portion. Upon rotation about an axis at the side of the restriction partition away from the closed end of the cup-shaped member, the mercury is forced through the restriction partition into the light cup-shaped member. The pressure of centrifugal force acting upon the mercury within the cup-shaped member is exerted against the frangible neck portion. When a volume of mercury proportional to the required time delay has flowed through the restriction partition, the pressure of centrifugal force breaks the shorting strip at the frangible portion to open the electrical circuit.

These and other objects, advantages and novel features of the invention will be apparent from the following description and the accompanying drawings wherein a preferred form of the invention is shown and described.

50 In the drawing:

Fig. 1 is a sectional view through a rotating device in which a centrifugal unshorting switch embodying the invention is supported;

Fig. 2 is a longitudinal sectional view through a centrifugal switch embodying the invention;

Fig. 3 is a sectional view on line 3—3 of Fig. 2; and Fig. 4 is a sectional view on line 4—4 of Fig. 2.

Referring to Fig. 1 there is shown a rotating member 10 which may be a spinning projectile or an element mounted upon a suitable power means such as the shaft of a motor. The rotating member 10 is formed with a cavity 11 in which a centrifugal unshorting switch 12 is positioned with the end of the switch through which the terminals 13 protrude closest to the axis of rotation of the member 10. The invention is particularly concerned with the centrifugal switch 12 and the means of breaking the electrical circuit between the two terminals 13. In rotation of the member 10 centrifugal force will be set up lengthwise of the switch 12 in a downward direction as shown in Fig. 2.

In a preferred embodiment of the invention shown in detail in Figs. 2 to 4 a hollowed inner cup 20 constructed

of metal having an extremely low tendency to amalgamate with mercury, preferably stainless steel, is counter-bored at the open end thereof to form a larger diameter section 21 into which two disks 22 and 23 are assembled, and the open end of the inner cup 20 is crimped to clamp 5 the disks 22 and 23 in close contact within the larger diameter section 21. The disks 22 and 23 are also constructed of metal having an extremely low tendency to amalgamate with mercury, preferably stainless steel, and the abutting surfaces 24 and 25 thereof respectively are 10 roughened by sand blasting or etching as disclosed in my application Serial No. 165,976 to form a foraminous orifice between the surfaces which prevents the passage of a body of mercury normally contained within the inner cup 20 at atmospheric pressure under the blows 15 and impacts occurring during normal handling but which passes mercury under the pressure of centrifugal force. A plurality of holes 26 drilled in the top surface of the disk 22 along the circumference of a circle concentric with the disk 22 open into an annular distribution groove 27 formed in the roughened face of the disk 22. A central hole 28 is provided axially through the disk 23. The foraminous orifice formed between the abutting surfaces 24 and 25 prevents the radial flow of mercury from the annular distribution groove 27 thence between these surfaces and out of the hole 28 at atmospheric pressure under the blows and impacts occurring during normal 20 handling.

The end of the inner cup 20 across which the disks 22 and 23 are sealed extends into the open end of a thin 30 larger diameter outer cup 30 to telescope said cups together with the opposite ends thereof closed. The light outer cup 30 constructed of suitable insulating material such as a phenolic resin is adapted to slide axially of the inner cup 20 away from the axis of rotation of the member 10 in response to the centrifugal force set up by rotating the switch 12 by means of the member 10.

A thin, narrow shorting strip 31 of suitable metal having a high conductivity such as copper which narrows to a restricted neck portion 32 at the center thereof is utilized to effect the desired short circuit. A headed member 33 of suitable insulating material such as a phenolic resin is formed with an upwardly extending shank 34 having an indentation 35 hollowed in the end thereof to receive the rounded closed end 36 of the outer cup 30. An annular ring 37 of suitable insulating material such as a phenolic resin is formed with diametrically opposite vertical grooves 38 and 39 in the inner and outer circumferences thereof respectively to receive the shorting strip 31. The inner diameter of the ring 37 is slightly larger than the diameter of the shank 34, and the restricted neck portion 32 of the shorting strip 31 is stretched taut across the indentation 35 by placing the shorting strip 31 above the shank 34 and then pressing the ring 37 over the shank 34 with the shorting strip 31 fitting in the grooves 38 until the ring 37 is seated against the head of the member 33. After the ends of the shorting strip 31 are bent upward to fit within the grooves 39 in the outer circumference of the ring 37, a tubular sleeve 40 of suitable insulating material such as a phenolic resin is disposed around the ring 37 and against the head of the member 33. The assembled elements are then positioned within a steel can 41 with the headed member 33 seated against the closed end 42 of the can 41 and with the ends of the shorting member 31 projecting upwardly toward the open end of the can 41 and toward the axis of rotation of the member 10.

A groove 44 is cut in the outer periphery near the closed end of the inner cup 20 to receive a closure washer 45 of suitable insulating material formed with two diametrically opposite rectangular holes 46 through the annulus thereof. When the telescoping inner cup 20 and outer cup 30 are assembled within the sleeve 40 with the closed end 36 of the outer cup 30 disposed adjacent the restricted neck portion 32 of the shorting strip 31 and

with the closure washer 45 seated against the upper end 47 of the sleeve 40, the vertical arms of the shorting strip 31 extend through the rectangular holes 46 in the closure washer 45 and end in soldering terminals 13 to allow external electrical circuit connections. The edge of the can 41 at the open end thereof is crimped against the closure washer 45 to retain the elements within the can 41. The inner cup 20 and outer cup 30 are in telescoped sliding engagement, but as the washer 45 abuts against the upper edge 47 of the sleeve 40, the inner cup 20 is fixedly positioned and only the outer cup 30 is free to move away from the axis of rotation of the member 10 in response to the centrifugal force set up by rotating the switch 12 by means of member 10. The shorting strip 31 narrows to a restricted neck portion 32 at the center thereof to form a frangible link which can be broken by exerting sufficient pressure against the outer cup 30 to bend the shorting strip 31 to the contour of the hollowed indentation 35.

From the foregoing description it will be observed that there is provided a centrifugal switch in which the desired electrical short circuit is obtained by the use of a narrow continuous strip of copper formed with a restricted frangible neck portion instead of relying upon a conductive fluid to bridge the gap between two contacts. It will be further observed that the mercury is initially contained within a stainless steel cup out of contact with any copper or other metal parts which have a strong tendency to amalgamate with the mercury, thus avoiding any possibility of contamination and the formation of sludge which might adversely affect the flow characteristics of the conductive fluid.

In the operation of the switch, the multiplicity of orifices formed between the roughened abutting surfaces 24 and 25 of the stainless steel disks 22 and 23 are capable of preventing the passage of mercury at atmospheric pressure under the blows and impacts from normal handling as described in my above mentioned application, but are capable of passing the mercury in response to the centrifugal force set up by rotating the switch 12 by means of the member 10. The resistance to the flow of mercury from the annular groove 27 thence between the surfaces 24 and 25 and out of the central hole 28 can be accurately controlled by varying the size of the grit if sand blasting is utilized to coarsen the surfaces 24 and 25. By sand blasting the surfaces 24 and 25 to a roughness proportional to the required time delay in the flow of a given volume of mercury out of the inner cup 20 into the outer cup 30 through the multiplicity of orifices between these surfaces, it is possible to obtain time delays ranging from 0.1 second to 3.0 seconds under a given pressure head.

The centrifugal unshorting switch 12 is positioned within the cavity 11 with the closed end 36 of the outer cup 30 away from the axis of rotation of the member 10. The pressure of centrifugal force acting upon the light outer cup 30 is insufficient to cause the shorting strip 31 to break at the frangible portion 32 if no mercury has flowed into the outer cup 30. Nor will the frangible portion 32 rupture under impacts of the light outer cup 30 during normal handling. As the mercury flows into the light outer cup 30 under spin conditions, the stress exerted against the frangible portion 32 gradually increases, and when a volume of mercury proportional to the required time delay has flowed into the outer cup 30, the pressure of centrifugal force acting against the outer cup 30 is sufficient to break the shorting strip 31 at the frangible portion 32. As described hereinbefore, the indentation 35 is hollowed to receive the rounded closed end 36 of the outer cup 30 so that the broken ends of the shorting strip 31 are compressed by the outer cup 30 against the contour of the indentation 35 to move the broken ends further apart and prevent the re-establishment of a short circuit across the terminals 13.

A positive short circuiting connection is thus provided through the continuous copper shorting strip 31 until sufficient mercury has flowed into the outer cup 30 under the pressure of centrifugal force to rupture the shorting strip 31 at the frangible portion 32. The mercury is initially contained within a closed cup constructed entirely of stainless steel and having no copper or other metal parts which have a strong tendency to amalgamate with the mercury. Thus any possibility of a high resistance electrical short circuit occurring after a sufficient volume of mercury has flowed through the restriction partition to open the electrical circuit due to the deposition of film of an oxide of mercury across the switch has been eliminated. Furthermore, the embodiment avoids the danger of erratic time delays due to contamination and the formation of a sludge within the switch which might adversely affect the flow characteristics of the mercury.

While the embodiment of the present invention as herein described constitutes a preferred form, it is to be understood that other forms might be adopted, all within the scope of the claims which follow. It will be evident to those skilled in the art that the use of a continuous shorting strip formed with a frangible portion could be applied to telescoped containers having a fibrous or sintered metal time delay element sealed across the open end of the smaller container.

I claim:

1. A centrifugal unshorting switch comprising a pair of cup-shaped containers in telescoped sliding engagement with closed ends spaced apart and with the open end of the smaller of said containers adapted to be sealed, time delay means sealed across the open end of the smaller container for retarding the flow of mercury out of the smaller into the larger container, a body of mercury within the smaller container, a metal shorting strip formed with a frangible portion stretched across an indentation in front of the closed end of the larger container, said frangible portion being strong enough to withstand the impacts from said larger container due to blows and impacts occurring during normal handling as well as the stress caused by centrifugal pressure exerted against said larger container before mercury has flowed into the larger container but weak enough to break under the stress caused by centrifugal pressure exerted against said larger container after a volume of mercury proportional to the required time delay has flowed through said time delay means.

2. A centrifugal unshorting switch comprising a pair of cup-shaped containers in telescoped sliding engagement with closed ends spaced apart and with the open end of the smaller of said containers adapted to be sealed, a pair of stainless steel disks sealed across the open end of the smaller container with the flat surfaces thereof abutting, one of said disks having a central opening therein, the other disk having a plurality of apertures arranged in a circle concentric with said disk opening into an annular groove provided in the abutting surface thereof, at least one of the abutting surfaces being coarsened by sand blasting or etching to form a foraminous orifice between said surfaces which allows passage of mercury under centrifugal pressure but prevents passage of mercury at atmospheric pressure under the blows and impacts occurring during normal handling, a body of mercury within said smaller container, and a shorting strip of thin metal formed with a frangible portion stretched across an indentation in front of the closed end of the larger container, said frangible portion being sufficiently strong to withstand the stresses caused by centrifugal force acting against the larger container before mercury has flowed into the larger container and to withstand the stresses caused by the larger container hitting against the frangible portion under blows and impacts occurring during normal handling but weak enough to break under the stresses caused by centrifugal force acting against the larger con-

tainer after a volume of mercury proportional to the required time delay has flowed through said foraminous orifice into said larger container.

3. A centrifugal unshorting switch comprising a pair of cup-shaped containers in telescoped sliding engagement with the open end of the smaller of said containers adapted to be sealed and enclosed within the larger of said containers, a body of mercury within the smaller of said containers adapted to flow into the larger of said containers and cause axial movement thereof, means sealed across the open end of said smaller container for retarding the flow of mercury out of said smaller and into the larger container, and a shorting strip of metal formed with a frangible portion stretched across an indentation in front of the closed end of the larger container and adapted to be engaged and broken by motion of the larger container toward the indentation.

4. A centrifugal unshorting switch comprising a rotating member, a pair of open-ended containers in telescoped sliding engagement with the open end of the smaller of said containers adapted to be sealed and facing the closed end of the larger container, said containers being mounted on said rotating member with the axis of said containers radial to the axis of rotation and with the closed end of the larger container away from said axis of rotation, mercury within said smaller container, means sealed across the open end of said smaller container for retarding the flow of mercury out of said smaller and into said larger container, centrifugal force acting on the mercury that flows into said larger container tending to cause axial movement thereof radially outward from said axis of rotation, and a metallic shorting strip formed with a frangible portion mounted on said rotating member across an indentation in front of the closed end of the larger container and adapted to be engaged and broken by the radially outward movement of said larger container.

5. An unshorting switch, comprising a pair of open-ended containers in telescoped sliding engagement with the open end of the inner of said containers adapted to be sealed and facing the closed end of the outer container, a body of mercury within said inner container adapted to flow into said outer container and cause axial movement thereof, means sealing the open end of said inner container, means associated with said sealing means for controlling the flow of mercury from said inner into said outer container, and a rupturable conducting strip positioned in the path of movement of said outer container and adapted to be engaged and broken thereby after a predetermined amount of mercury has flowed into said outer container.

6. A centrifugal unshorting switch comprising a rotating member, a pair of open-ended containers in telescoped sliding engagement with the open end of the inner of said containers adapted to be sealed and facing the closed end of the outer container, said containers being mounted on said rotating member with the axis of said containers radial to the axis of rotation and with the closed end of the outer container away from said axis of rotation, a body of mercury within said inner container, means sealing the open end of said inner container, means associated with said sealing means for controlling the flow of mercury from said inner into said outer container, the flow of mercury into said outer container causing axial movement thereof, and a rupturable conducting strip on said rotating member positioned in the path of movement of said outer container and adapted to be engaged and broken thereby after a predetermined centrifugal force, due to the mercury within said outer container, is attained.
